N FOR A HOLDER FOR CIGARETTE-PAPERS.

Design No. 13,395, dated November 7, 1882.

UNITED STATES PATENT OFFICE.

JACOB L. HAAS, OF NEW YORK, N. Y., ASSIGNOR TO WEMPLE & CO., OF SAME PLACE.

DESIGN FOR A HOLDER FOR CIGARETTE-PAPERS.

SPECIFICATION forming part of Design No. 13,395, dated November 7, 1882.

Application filed October 4, 1882. Term of patent 3½ years.

To all whom it may concern:

Be it known that I, JACOB L. HAAS, of New York, in the county and State of New York, have invented a new and original Design for a Holder for Cigarette-Papers, of which the following is a specification.

The invention relates to a new and original design for the covers of a holder for cigarette-paper or other similar articles; and it consists in the novel grouping of figures hereinafter more fully described.

The accompanying photograph is a view of the covers of a holder for cigarette-paper, on which covers are imprinted my new design. On one half of the photograph is represented a part of my design, showing a match-pocket containing matches, and having a representation of a piece of sand-paper with scratches on its face, and the open end of a cigarette-pocket,

and the exposed ends of several cigarettes contained in said pocket. The other half of the photograph represents the bill and stamp pockets of a pocket-book, ornamented as shown, and the exposed portions of a check and stamps contained in said pockets. My design consists in the grouping of the several parts, as shown, as an ornamentation to be imprinted upon the covers of holders for cigarette-paper and similar articles.

I claim—

The design for the covers of a holder for cigarette-paper, substantially as shown and described.

JACOB L. HAAS.
